DESIGN FOR A SPOON OR OTHER ARTICLE OF FLATWARE

James Russell Price, Cranston, R. I., assignor to
Gorham Manufacturing Company, Providence,
R. I., a corporation of Rhode Island

Application June 1, 1940, Serial No. 92,739

Term of patent 14 years

To all whom it may concern:

Be it known that I, James Russell Price, a citizen of the United States of America, of 2335 Cranston Street, Cranston, Rhode Island, have invented a new, original, and ornamental Design for a Spoon or Other Article of Flatware, of which the following is a specification, reference being had to the accompanying drawing, forming part thereof.

Figure 1 is a front elevation of a spoon or other article of flatware showing my new design;

Figure 2 is a side elevation of the same; while Figure 3 is a rear elevation of the same; and Figures 4, 5 and 6 are cross sections of the spoon or other article of flatware of Figure 1 as taken on lines 4—4, 5—5 and 6—6, respectively.

I claim:

The ornamental design for a spoon or other article of flatware, substantially as shown.

JAMES RUSSELL PRICE.
